CLAIM

The ornamental design for the holder for a transportation robot, as shown and described.

DESCRIPTION

FIG. 1 is a bottom, front, left perspective view of a holder for a transportation robot showing our new design;

FIG. 2 is a top, front, left perspective view thereof;

FIG. 3 is a left side view thereof;

FIG. 4 is a right side view thereof;

FIG. 5 is a top view thereof;

FIG. 6 is a bottom view thereof;

FIG. 7 is a rear view thereof; and,

FIG. 8 is a front view thereof.

The broken lines in the figures show portions of the holder for a transportation robot that form no part of the claimed design.

1 Claim, 5 Drawing Sheets(56)
